Primary Examiner — Bridget L Eland*(74) Attorney, Agent, or Firm* — Rabin & Berdo, P.C.(57) **CLAIM**

The ornamental design for a medical mirror, as shown and described.

DESCRIPTION

FIG. 1 is a front view of a medical mirror showing my new design;

FIG. 2 is a top view thereof;

FIG. 3 is a bottom view thereof;

FIG. 4 is a left side view thereof;

FIG. 5 is a right side view thereof;

FIG. 6 is a rear view thereof;

FIG. 7 is a perspective view thereof;

FIG. 8 is a front view of a second embodiment of a medical mirror showing my new design;

FIG. 9 is a top view thereof;

FIG. 10 is a bottom view thereof;

FIG. 11 is a left side view thereof;

FIG. 12 is a right side view thereof;

FIG. 13 is a rear view thereof;

FIG. 14 is a perspective view thereof;

FIG. 15 is a front view of a third embodiment of a medical mirror showing my new design;

FIG. 16 is a top view thereof;

FIG. 17 is a bottom view thereof;

FIG. 18 is a left side view thereof;

FIG. 19 is a right side view thereof;

FIG. 20 is a rear view thereof; and,

FIG. 21 is a perspective view thereof.
